(57) **CLAIM**

We claim as our invention the ornamental design for a mold, as shown and described herein.

DESCRIPTION

FIG. 1 is a perspective view of a mold of a first embodiment in a closed position;

FIG. 2 is a front view of the mold of a first embodiment in a closed position;

FIG. 3 is a side view of the mold of a first embodiment in a closed position;

FIG. 4 is a top view of the mold of a first embodiment in a closed position;

FIG. 5 is a bottom view of the mold of a first embodiment in a closed position;

FIG. 6 is an exploded, perspective view of the mold of a first embodiment.

FIG. 7 is a perspective view of a mold of a second embodiment in a closed position;

FIG. 8 is a front view of the mold of a second embodiment in a closed position;

FIG. 9 is a side view of the mold of a second embodiment in a closed position;

FIG. 10 is a top view of the mold of a second embodiment in a closed position;

FIG. 11 is a bottom view of the mold of a second embodiment in a closed position; and,

FIG. 12 is an exploded, perspective view of the mold of a second embodiment.
